UNITED STATES PATENT OFFICE.

WILLIAM F. McDOWELL, OF GARDNER, MASSACHUSETTS.

WOODWORKING MACHINERY.

1,163,098.

Specification of Letters Patent.

Patented Dec. 7, 1915.

Application filed January 14, 1915. Serial No. 2,239.

To all whom it may concern:

Be it known that I, WILLIAM F. McDOWELL, a citizen of the United States, residing at Gardner, in the county of Worcester and State of Massachusetts, have invented new and useful Woodworking Machinery, of which the following is a specification.

This invention relates to a wood working machine capable of general application but more particularly designed for grooving the upper back rail of the chair shown in my pending application, Serial No. 774,605, filed June 19, 1913.

It is the object of my invention to provide improved devices for positioning and holding the work and for moving the same relatively to the cutting tool.

With this object in view my invention relates to certain devices, arrangements and combinations of parts which will be hereinafter described and more particularly pointed out in the appended claims.

A preferred form of the invention is shown in the drawings in which—

Figure 1 is a front elevation of the machine; Fig. 2 is a detail section taken on the line 2—2 in Fig. 1; Fig. 3 is a top plan view of the machine; Fig. 4 is a side elevation thereof; Fig. 5 is a partial vertical section substantially on the line 5—5 in Fig. 1; Fig. 6 is an enlarged detail of one of the work gages; Fig. 7 is a detail view in elevation of a part of a chair back rail, for the production of which the machine is particularly designed, and Fig. 8 is a sectional view taken on the line 8—8 in Fig. 7.

As shown in the drawings, my machine comprises a base 10 having fixed bearings 11 and 12 (Fig. 3) for a tool spindle 13. The spindle 13 is provided with a pulley 14 which may be belt-driven from any convenient source of power. The spindle 13 also supports the rotating cutting tool 15 at one end thereof, the spindle being provided with suitable shoulders and collars for preventing longitudinally displacement thereof. Upon its front side, the base 10 has a projection 10^a (Fig. 2) upon which are secured guide strips 16. The strips 16 serve to position a vertically movable plate 17 and one strip 16 may be formed with an adjustable gib 16^a for close adjustment to the plate 17.

A bracket 18 is secured to or formed integral with the plate 17 and supports the

table 19 upon its upper face. The table 19 will ordinarily be formed of wood and is provided at each end with depending members 20 and 21 (Fig. 1) which are retained in proper relative position by brackets 22 and 23. The members 20 and 21 have ways 24 and 25 (Figs. 1, 3 and 4) on their outer surfaces, serving as guides for vertically sliding plates 26 and 27 to which are secured the table extensions 28 and 29, these extensions being reinforced by brackets 30. The plates 26 and 27 are slotted as indicated at 31 (Fig. 4) and are held in adjusted position by binding nuts 32 which secure the plates to the depending members 20 and 21.

A downwardly-extending bar 33 (Fig. 1) is secured to the plate 17 or the bracket 18, and is provided at its lower end with a cross bar 34. A pair of heavy spiral springs 35 are secured at their upper ends to rods 36 projecting forwardly from the upper part of the base 10 and at their lower ends are connected to the cross bar 34. The springs 35 therefore act to normally retain the table 19 at its upper limit of travel. Any suitable stop, such as an arm 37 mounted on the bar 33, may be provided to limit the upward movement.

A foot pedal 38 extends through a slot 39 (Fig. 1) in the lower part of the base and is movable about a fixed pivot 40 (Fig. 4) at the back of the machine. Near its forward end the lever 38 is pivotally connected by a link 41 to the lower end of the bar 33, the pedal thus being effective to move the table downwardly past the cutter 14 against the resistance of the springs 35.

For positioning and holding the work, a pair of upright guides 42 (Figs. 1 and 4) are secured to the table 19, these guides in their preferred form being provided with base portions 43 (Fig. 5) extending beneath the table and secured in recesses therein. The guides 42 serve to position the work in one direction and may be normal to the surface of the table or slightly inclined thereto as determined by the nature of the work. It will be noted that these guides are positioned closely adjacent to the cutter 15 and on each side thereof, so that the work is securely supported at the cutting point.

For clamping the work against the guides 42 I provide a plunger 44 (Fig. 5) slidable in a block 45 secured to the upper surface of

the table 19. Intermediate its ends the plunger 44 is cut away to provide a recess 46 adapted to receive a compression spring 47. A pin 48 in the block 45 extends through 5 the recess and provides a bearing for one end of the spring, the pin also limiting the rearward movement of the plunger.

The plunger and spring are confined within the block 45 by a cap 49 having upwardly 10 projecting ears 50 between which is pivotally mounted a hand lever 51 having a depending portion 52 adapted to engage the rear end of the plunger 44. At its forward end the plunger may have an enlarged head 15 53 and may also be suitably faced with leather or other suitable material 54 to prevent marring the work.

When the work is positioned between the guides 42 and the head 53 of the plunger 44, 20 downward movement of the lever 51 will force the plunger rearwardly to secure the work in position.

For positioning the work longitudinally, I provide a pair of stops 55 and 56 (Fig. 3) 25 formed of flexible material and secured in longitudinal grooves 57 in the upper surface of the table 19. Underneath the movable ends of the stops a tapered groove 58 (Fig. 6) is provided within which the end 30 of the stop may be received.

As previously stated, my machine is particularly designed for operating upon the upper back rail of a chair and it is necessary that it should be at all times operable upon 35 either end of the rail.

By the use of the yielding stops just described, either one of the stops may be utilized to position the rail and the other stop may be pushed downwardly by the work so 40 that it will lie below the surface of the table.

In Figs. 7 and 8 I have shown one end of a chair rail, for the production of which my machine is particularly designed. It will be seen that the rail 60 is provided with an 45 undercut groove 61 extending partially across the back side of the rail, a similar groove being provided at the opposite end of the rail (not shown). As shown in the drawings, the groove 61 is not exactly normal to the lower surface of the rail. This 50 relation is determined by the angle at which the back legs of the chair meet the upper rail and it will be seen that the angle will be reversed at the opposite end of the rail.

55 In order that the groove in the rail may be formed at any desired angle I have provided the vertically adjustable table extensions 27 and 28, by the use of which the outer end of the rail may be raised or lowered relatively

to the end upon which the cutter is operating.

By adjusting the extensions at the same height relative to the table 19 and resting the work alternately upon the extensions 28 and 29, the grooves will be formed at equal but reversed angles at the opposite ends of the rail. When one end of the rail is raised upon the extension 28 the opposite end of the rail will rest upon the table 19 and will engage and be positioned by the stop 55, the intermediate portion of the rail resting upon the stop 56 and depressing the same to the level of the table. Having the work thus positioned, the handle 51 is pushed downwardly to clamp the work against the guides 42 and the foot pedal 38 is operated to carry the work downwardly past the cutter 15. Any suitable adjustable stop such as the screw 62 engaging the arm 37 may constitute means for limiting the downward movement of the table 19.

Having thus described my invention it will be evident that changes and modifications can be made therein without departing from the spirit and scope thereof as set forth in the claims and I do not wish to be limited to the details herein described but

What I do claim is—

1. A wood working machine comprising a base, a tool-carrying spindle rotatable in fixed horizontal bearings on said base, a work support vertically movable in fixed guides on said base in a plane normal to said spindle, and means for positioning and holding the work on said table, said table comprising a center portion and extensions adjustable vertically relatively to said center portion, said extensions being effective to vary the angle at which the work is supported upon the center portion. 100

2. A wood working machine comprising a base, a tool-carrying spindle rotatable in fixed horizontal bearings on said base, a work support vertically movable in fixed guides on said base in a plane normal to said spindle, and means for positioning and holding the work on said table, said means comprising flexible end gages yieldingly movable to inoperative position and extensions adjustable relatively to the table to vary the angular position of the work thereon. 105

In testimony whereof I have hereunto set my hand, in the presence of two subscribing witnesses.

WILLIAM F. McDOWELL.
